FIG. 3

UNITED STATES PATENT OFFICE

2,329,866

CIGARETTE CONTAINER

John H. Van Sickels, Montreal, Quebec, Canada,
assignor to Imperial Tobacco Company of
Canada Limited, Montreal, Quebec, Canada

Application September 23, 1941, Serial No. 411,998

4 Claims. (Cl. 229—27)

This invention relates to improvements in cigarette containers of the dispensing slide type, the object being to provide improved means for dividing the dispensing slide into a plurality of compartments dimensioned to ensure that the cigarettes placed therein will always be maintained in a substantially upright position, that is to say, will be prevented from toppling over to a position where they are difficult to remove and are apt to become damaged.

The conventional cigarette container of the dispensing slide type provides a single cigarette receiving compartment which is so dimensioned that, after a certain number of cigarettes have been removed from the compartment, the remaining cigarettes are free to topple over to an inclined position such that they are difficult to remove and are subject to damage. This condition obtains regardless of whether the cigarettes are arranged in the compartment in the form of separately wrapped bundles or are merely packed in said compartment without any wrapping whatsoever. As previously stated the present invention eliminates this difficulty by sub-dividing the dispensing slide into a plurality of smaller compartments, in which even a single cigarette will be retained in a substantially upright position.

Proceeding now to a more detailed description reference will be had to the accompanying drawing in which—

Figure 1 is a perspective view of my improved dispensing slide.

Figure 2 is a perspective view showing the slide as it appears just prior to being inserted in the outer case.

Figure 3 is a sectional view along the line 3—3 of Fig. 2.

Fig. 4 is a view similar to Fig. 1 but showing a slight modification.

Except as hereinafter specified, the container shown in the present drawing is of a known type comprising an outer case 5 and a dispensing slide 6, the latter presenting a rear wall 7, a front wall 8, side walls 9, a bottom wall 10, and a top wall 11, the latter wall being provided with a depending flap extension 12.

According to the present invention the rear wall 7 of the dispensing slide is stamped to provide a panel 14 adapted to be bent inwardly along the vertical crease line 15. The front wall 8 is stamped to provide a slot or recess 16 extending substantially from the bottom edge to the upper edge, said slot being opposite the crease

line 15 and adapted to receive therein the front edge portion of the panel 14. The width of the panel 14 from the hinge 15 to its front edge is slightly greater than the depth of the dispensing slide so that when the panel is swung on the hinge to a vertical position, it will be held in place by the side walls of the slot or recess 16.

As shown in Figs. 2 and 3, the panel 14 engaged in the slot 16 serves as a partition wall between the bundles of cigarettes 17 and 18, and serves to keep the cigarettes of one bundle from shifting laterally when the cigarettes in the other bundle have been removed. Instead of being provided with the slot 16, the front wall of the dispensing slide may be provided with a groove or recess 16a to receive the front edge of the panel 14.

In the drawing I have shown the preferred embodiment of my invention to be a single panel or partition wall located in the center of the slide. It is to be understood, however, that two or more panels suitably spaced apart, depending on the width of the container, is within the scope of my invention.

Having thus described my invention, what I claim is:

1. A cigarette container comprising a rectangular outer case open at top and bottom and a one piece rectangular dispensing slide of the folded blank type arranged in said case so as to be a close sliding fit therein, said slide comprising a rear wall, side walls hinged to the side edges of the rear wall, a top wall hinged to the upper edges of the rear wall, a bottom wall having its rear edge hinged to the lower edge of the rear wall and being free of attachment to the side walls, a front wall hinged to the front edge of the bottom wall and a vertical partition member attached to said rear wall and extending forwardly therefrom into a vertical slot provided in said front wall whereby said partition member is held against lateral displacement, said outer case serving to hold the front and rear walls of the slide against relative outward movement to thereby prevent accidental withdrawal of said partition from said slot.

2. A cigarette container comprising a rectangular outer case open at top and bottom and a one piece rectangular dispensing slide of the folded blank type arranged in said case so as to be a close sliding fit therein, said slide comprising a rear wall, side walls hinged to the side edges of the rear wall, a top wall hinged to the upper edges of the rear wall, a bottom wall hav-

ing its rear edge hinged to the lower edge of the rear wall and being free of attachment to the side walls, a front wall hinged to the front edge of the bottom wall and a vertical partition member attached to said rear wall and extending forwardly therefrom into a vertical groove provided in the rear surface of the front wall whereby said partition member is held against lateral displacement, said outer case serving to prevent relative outward movement of the front and rear walls of the slide and to thereby prevent accidental withdrawal of the partition from said groove.

3. A cigarette container comprising a rectangular outer case open at top and bottom and a one piece rectangular dispensing slide of the folded blank type arranged in said case so as to be a close sliding fit therein, said slide comprising a rear wall, side walls hinged to the side edges of the rear wall, a top wall hinged to the upper edge of the rear wall, a bottom wall having its rear edge hinged to the lower edge of the rear wall, a front wall hinged to the front edge of the bottom wall, a vertical partition attached to the rear wall and extending forwardly therefrom, said front wall being provided with means whereby interfitting engagement is established between said front wall and the front edge of said partition to hold the latter against lateral

movement, said outer case serving to hold the front and rear walls of the slide against relative outward movement and to thereby prevent said partition being accidentally withdrawn from its interfitting engagement with said front wall.

4. A cigarette container comprising a rectangular casing open at top and bottom and a one piece rectangular dispensing slide of the folded blank type arranged in said casing so as to be a close sliding fit therein, said slide comprising a rear wall, side walls hinged to the side edges of the rear wall, a top wall hinged to the upper edge of the rear wall, a bottom wall having its rear edge hinged to the lower edge of the rear wall, a front wall hinged to the front edge of the bottom wall, a vertically extending partition attached to and extending forwardly from the rear wall at right angles thereto, the width of said partition, as measured between its front and rear edges, being slightly greater than the width of said bottom wall and said front wall being provided with a slot in which the front edge portion of the partition is fitted, said slide serving to prevent relative outward movement of the front and rear walls of the slide to thereby prevent accidental withdrawal of the partition from said slot due to such movement.
